(57) **CLAIM**

The ornamental design for a record album frame, as shown and described.

DESCRIPTION

FIG. 1 is a perspective view of a record album frame according to the present invention used to display a phonograph record;

FIG. 2 is an exploded front perspective view of the record album frame;

FIG. 3 is a perspective view of the back of the record album frame, shown with the removable mounting post removed for completeness of illustration;

FIG. 4 is a side view of the record album frame, shown with the removable mounting post removed for completeness of illustration;

FIG. 5 is a side view of the record album frame with the mounting post secured on the base member;

FIG. 6 is a cross-sectional side view of the record album frame with the mounting post secured on the base member;

FIG. 7 is an enlarged view of the rear of the record album frame;

FIG. 8 is an enlarged perspective view of the record mounting post;

FIG. 9 is an enlarged cross-sectional view of the mounting post; and,

FIG. 10 is an enlarged rear view of the mounting post interlocked with the record album frame.

The top and bottom of the frame are unornamented.

The broken lines shown in FIGS. 7 and 10 are included for the purpose of illustrating portions of the record album frame that form no part of the claimed design.

1 Claim, 5 Drawing Sheets
